[57] CLAIM

The ornamental design for an automobile lock for attachment to a steering wheel and a steering column-mounted gearshift lever, as shown and described.

DESCRIPTION

FIG. 1 is a perspective view of an automobile lock for attachment to a steering wheel and a steering column-mounted gearshift lever showing my new design; FIG. 2 is an inverted perspective view thereof; and FIG. 3 is a perspective view thereof, with the lock shown in its engaged position and with the key element removed.

FIG. 1.

FIG. 2.

FIG. 3.
